UNITED STATES PATENT OFFICE.

CLARENCE S. BODEN, OF SAN FRANCISCO, CALIFORNIA, ASSIGNOR TO BODEN'S AUTOMATIC HAMMER CO., A CORPORATION OF CALIFORNIA.

TACKING AND LASTING PINCERS.

1,090,514.

Specification of Letters Patent. Patented Mar. 17, 1914.

Application filed October 26, 1911. Serial No. 656,950.

To all whom it may concern:

Be it known that I, CLARENCE S. BODEN, a citizen of the United States, and residing at San Francisco, in the county of San Francisco and State of California, have invented certain new and useful Improvements in Tacking and Lasting Pincers, of which the following is a specification.

This invention relates to hand tools of the type known as lasting pincers, and has particular reference to means for supplying and driving tacks or equivalent fastenings by means of the same implement as that which grasps the leather during the lasting operation.

The principal object of the present invention is to provide lasting pincers with means whereby one of a plurality of tacks or nails carried by the tool may be driven through the leather into the last, another tack or nail being automatically fed to position ready to be driven by another blow.

Further objects of the invention are to provide certain improvements in hand operated tools of the character mentioned as will be hereinafter explained.

To these ends the invention consists in the construction and combination of parts substantially as hereinafter described and claimed.

Of the accompanying drawings, which form a part of this specification,—Figure 1 is a side elevation of a tool constructed according to my invention, the movable member of the head being indicated by full lines in one position, and dotted lines in another position. Fig. 2 represents a sectional elevation. Fig. 3 is a plan view. Fig. 4 represents a section on line 4—4 of Fig. 1 on a larger scale. Fig. 5 is a perspective view of the feeding pawl. Fig. 6 represents a section on line 6—6 of Fig. 1.

Similar reference characters indicate the same or similar parts in all of the views.

As usual with tools of the pincer type, two handles are provided, the handle 10 projecting rigidly from the portion 11 of the head of the tool. Movably connected with the rigid part 11 of the handle is the part 12 which has side pieces or plates that overlap the member or part 11, the side pieces or plates preferably fitting suitable ways carried by the other portion 11 of the head, as best shown in Figs. 1 and 3. The side pieces or plates are formed with slots

13 through which guiding screws 14 pass into the part 11.

The part 12 is provided with a substantially central aperture 15, through which the tacks are driven. Secured to the member 11 of the head is a driver 16, the lower end of said driver being in alinement with the aperture 15. Slidably mounted in the member 11 is a plunger 17 which is projected by means of a spring 18. The lower end of said plunger bears against a suitable shoulder or ledge provided therefor on the movable part 12 of the head, the said spring 18 and plunger 17 serving to tend to hold the two members of the head in the relative position indicated in Fig. 2 and by dotted lines in Fig. 1.

The member 11 of the head is provided with a projection or lug 19 having an inclined face 20, the latter constituting a cam to actuate the feeding pawl in one direction, preliminary to feeding, as presently described.

Mounted to reciprocate in a transverse opening on the member 12 of the head is a pawl 21, said pawl having one side face provided with a series of teeth 22 (Fig. 5) adapted to engage a plurality of tacks *a* carried by a strip *b* the rear end of said strip being supported in a manner hereinafter described.

The pawl 21 is formed with a recess or channel 23 extending longitudinally thereof, and a spring 24 is located in said channel and bears against one end of it, the other end of said spring being held by a lug 25 that is removably carried by the member 12 of the head in a manner hereinafter described. The spring 24 actuates the pawl in its feeding direction, to the extent determined by a stop which may consist of the head 26 of a screw (Fig. 4) mounted in a hole therefor in the member 12. Extending transversely of the member 12 of the head, and above the guideway for the pawl, is a transverse aperture 27 which serves as a guide for the tack strip *b*, said strip guide being open along a portion of its under side to permit the tacks *a* to be fed by the pawl 21 to a position where they will be successively in alinement with the driver 16.

The pawl 21 is normally held so that its teeth 22 will engage a plurality of the nails as best shown in Fig. 4 by means of the spring 28. This spring 28 readily yields to

permit the end of the strip to be inserted to place until the front nail of said strip is under the end of driver 16.

The tacks are carried by means of a paper strip *b*, the heads of said tacks being so attached to the paper strip that the tacks can be readily pushed out by the driver. In order to prevent any possibility of the paper strip retreating during the operation hereinafter described, I preferably employ a suitable spring detent such as indicated at 29 in Fig. 2, said detent engaging the upper surface of the strip *b*.

The member 11 of the head is formed with an aperture 30, across which is mounted a pivot 31 for the movable pincer jaw 32 which co-operates with a fixed pincer jaw 33, projecting from the member 11. The movable pincer jaw is provided with a handle 34 which is hollow, to contain the tack strip, said strip being so mounted in the hollow handle that when the said handle 34 is moved during the use of the two as pincers, the tack strip will not be shifted as to its relationship with the feeding mechanism with the member 12 of the head.

The member 12 is provided with a notch or recess 35 (Fig. 1) adapted to receive the end of a latch lever 36 connected to a lug 37 of the handle 10 by a pivot 38, and having its other end provided with a finger piece 39. A leaf spring 40 secured to the head as by a screw 41 has its free end bearing against the latch lever 36, so as to hold the tip thereof in the notch or recess 35 and to cause it to enter said notch whenever the latter is in position to receive it.

The lug 25 for one end of the spring 24 (Fig. 4) is carried by a block 42 which 40 partially enters the recess for the pawl, said block having a spring arm 43 bearing a lug 44 which engages a locking recess 45 formed in one side of the member 12 of the head. This last mentioned structure enables the 45 feeding mechanism to be quickly dis-assembled in the event of the choking up of the passage. To do this, it is only necessary to spring the arm 43 outwardly to release the lug 44 from the recess 45, after which the 50 block 42 and its lug 25 can be removed to permit the spring 24 and the pawl 21 to be slipped out of the chamber therefor in the movable member of the head.

It will be obvious of course, that the tool 55 can be used in the manner of ordinary lasting pincers and without being affected in any way by the fact that the tool is also a magazine hammer for driving tacks singly. When a tack is to be driven, the operator 60 grasping either one or both of the handles, swings the tool with the lower portion of the movable member 12 toward the work as a hammer head.

When the member 12 contacts with the 65 work, the momentum of the member 11

causes the driver 16 to detach the end tack from the strip and drive it through the aperture 15 into the work. After the tack has been detached and driven part way through the aperture 15, the inclined edge or cam 20 70 of the lug 19 slides downwardly across the end of the pawl 21, so as to slide said pawl toward the right of Fig. 2 far enough to cause the teeth 22 of the pawl to take a fresh hold of a plurality of tacks, but without 75 feeding the strip. The spring 28 yields sufficiently to permit the pawl 20 to swing when the latter is moving as just described, so that the ends of the teeth will pass over the tacks remaining attached to the strip. 80 The fact that the driver 16 has penetrated the tack strip *b* before the pawl 21 begins to move rearwardly to prepare for the next feed by taking a fresh hold tends to prevent such rearward movement of the pawl 85 from causing the tack strip to retreat. In effect therefore, the driver 16 acts as a detent to prevent backward movement of the tack strip. In case, however, the mutilation 90 of the paper strip by the driver should be such that said driver would not act definitely as a detent, the spring detent 29 will absolutely prevent backward movement of said strip. As soon as the tool is raised after 95 having driven a tack, the spring 18 acts to return the two parts of the head to their relative positions illustrated in Fig. 2, and as the cam lug 19 passes away from the end of the pawl 21, the spring 24 acts on the pawl to advance the tack strip to bring another tack into alignment with the driver 16, 100 ready for another tack-driving operation.

During the use of the tool as pincers, it is desirable that the two members of the head shall be locked against any relative sliding 105 movement and it is preferable that the locking shall be automatic after every tack-driving blow so that the tool will be normally in condition for use as pincers. As indicated by full lines in Fig. 1, the inner end 110 of the latch lever 36 is in the notch or recess 35 of the movable member 12, and is held therein by spring 40. Whenever the operator wishes to drive a tack, he first presses the finger-piece 39 inwardly toward the handle 115 10 so as to release the other end of lever 36 from locking recess 35 and then the spring 18, acting through plunger 17, instantly shifts the movable member to the position indicated by dotted lines in Fig. 1, and by full 120 lines in Fig. 2. The tack driving operation then causes the parts to assume their relative positions indicated by full lines in Fig. 1, the spring 40 instantly forcing the end 125 of the lever 36 into recess 35, so as to automatically lock the two members of the head so that no tack-driving operation can again be effected until the operator first actuates the latch lever 36. Of course, while the two members of the head are locked in inopera- 130

tive positions as just described, either end of the compound head of the tool can be used as a hammer, swinging the same like a hammer either by means of handle 10, or 5 by grasping both handles 10 and 34.

I claim:—

1. A tool of the character described, comprising a pair of crossed members pivoted together adjacent one end forming a pincer, 10 that part of each member lying on one side of the pivotal point forming a jaw, and that part of each member lying on the other side of the pivotal point forming a handle, tack driving means arranged on one side of said 15 members at the pivotal point, and a tack tape magazine arranged in the handle part of the other member.
2. In a combined pincer and hammer, the

combination of a pair of jaws hinged together with crossed handles, one jaw and 20 handle carrying a tack-driving head, the other jaw handle providing a tack-tape magazine, said head comprising two members 25 movably connected, one of said members forming a slide and the other member carrying a driver working through the slide, and means by which the tape from said magazine is fed to the head with the tacks in line with the driver.

In testimony whereof I have affixed my 30 signature, in presence of two witnesses.

CLARENCE S. BODEN.
